(57) **CLAIM**

The ornamental design for an electronic muscle stimulator glove, as shown and described.

DESCRIPTION

A glove for an electronic stimulation of subcutaneous muscle tissue using an electrically operable stimulator that delivers electrical pulses to at least one electrode, preferably about three, via the glove finger tips as illustrated, sufficient to cause the muscles to contract when the glove is topically placed at the discretion of the user, and result in a clinically perceptible increase in subcutaneous muscle tone when the glove is positioned on target skin areas and the device is activated.

FIG. 1 is a back, side perspective of an electronic muscle stimulator glove, showing my new design;

FIG. 2 is an inside perspective view thereof;

FIG. 3 is a side perspective view thereof;

FIG. 4 is another side perspective view thereof;

FIG. 5 is an end view thereof; and,

FIG. 6 is an end perspective view thereof, opposite that shown in FIG. 5.

The broken line showing of a glove cuff in the figures is for illustrative purposes only and forms no part of the claimed design.
